UNITED STATES PATENT OFFICE.

WIRT B. BOYCE, OF CHICAGO, ILLINOIS.

WINDOW-SHADE ADJUSTER.

1,073,323.

Specification of Letters Patent. Patented Sept. 16, 1913.

Application filed May 17, 1909. Serial No. 496,641.

To all whom it may concern:

Be it known that I, WIRT B. BOYCE, a citizen of the United States, residing at the city of Chicago, in the county of Cook and 5 State of Illinois, have invented a new and useful Improvement in Window-Shade Adjusters, of which the following is a specification.

My invention relates to devices for changing the vertical position of window shade rollers and adjusting them at any desired distance from the top of the window.

It is highly desirable, especially in living rooms and sleeping apartments, to obtain 15 ventilation from the top by lowering the upper sash, but when the shades are hung on stationary brackets, according to the usual custom, at the top of the casings they interfere with the air currents, are whipped about 20 and injured thereby, or must be rolled tightly, leaving the window entirely unshaded.

It is the object of my invention to permit 25 the shade roller itself to be lowered to clear the opening created by lowering the sash, while at the same time curtaining the lower part of the window as desired. Some devices with this end in view have been made, but they have been comparatively heavy, expensive and cumbersome, and usually have required special fitting of the shade rollers 30 and shades.

My present invention is simple and inexpensive, it is easily applied without shortening 35 or other modification of the shade roller or shades as already hung; injury to the shades when operated is guarded against and the lower part of the window completely curtained, while permitting free access, 40 light or air from the upper part as may be desired.

The principles of my invention are illustrated in the drawings, in which—

Figure 1 is an inside view of a window, 45 provided with my device. Fig. 2 is a vertical section of the same on the line 2—2 of Fig. 1. Fig. 3 is an enlarged detail of a bracket and a portion of the bracket guide.

Further describing my invention: 1 is the 50 casing of a window provided with a shade 2 mounted on the roller 3. Inside the window casing upon the stop is placed a bracket guide or runway 4. The latter in section should be somewhat that of a shallow U 55 having out-turned edges 5. A channel 6 is thus provided between the vertical walls 7 of the runway. Two brackets 8, as illustrated in Fig. 3, are provided. These brackets are provided on each side and at either end with wing pieces 9 which are turned 60 downwardly and inwardly so as form grooves within which run the out-turned edges of the channel pieces or guideways. A wing 10 should be formed on the bracket provided with the opening 11 by which a suspending cord may be attached, and a similar piece 12 at the lower end provides a check to engage a stop at the lower end of the guideway. Two of the described channel pieces should be placed at the upper part 65 of the window within the stops. The bracket shown in Fig. 3, has a rectangular opening to take the non-revoluble shaft of an ordinary spring roller. The other should have a circular opening to take the revolving 70 axis at the opposite end of the roller. I prefer to make the brackets as illustrated with edges 8' extended across and over the channels. The curtain roll is thus protected, and the brackets tend to guide the curtain as it 75 is rolled thereon. The lower end of the runways should be secured to the casing with a screw 12' which projects sufficiently to engage the stop 12 and prevent the brackets from leaving the lower end of the guide. 80 The upper portion of such guide should have a perforation through which a securing device may be passed into the casing, said device being adapted to engage with the wing or stop 10 and provided with a loop 85 through which a cord may be passed. One cord 13 is passed through the loop 14 and secured to the right hand bracket. Another cord 15 is secured to the left hand bracket, passed through the loop 16, and also through 90 the loop 14, at a little distance below which it should preferably be knotted to the cord 13. Both cords then extend down the inside of the window where they are attached to a hook 17. The adjustments of the parts 95 to the window frame may be made after removing a shade when fitted thereto in the ordinary manner. When the parts are placed as described, one trunnion of the roller is placed in the appropriate opening in one 100 bracket and the other bracket is raised to allow the other trunnion to be inserted therein. The bracket is then dropped and the adjustment is complete. It will be seen that the channel of the runway provides a space 105 adapted to take the trunnions of an ordinary window shade roller, whereby free move-

ment up and down is permitted. The same channel provides clearance for the cord attaching lip and stop 10 and the lower stop 12.

I claim:

- 5 In a window shade adjuster, stationary channel-shaped guides secured to the window casing and provided with outwardly turned flanged edges, brackets slidable on said guides restrainingly engaging said sides,
- 10 each bracket comprising an apertured plate having its ends provided with inwardly turned lips receiving the outwardly turned edges of the guide therein, said plate having side projections extending beyond the guides

and constituting means to guide the shade 15 in the winding and unwinding thereof on its roller, an inwardly-extending stop at each end of each bracket projecting into the channel of the guide, and supporting means in the form of cords attached to the lugs of 20 said brackets.

In witness whereof, I have hereunto set my hand, this 14th day of May, A. D. 1909, in the presence of two subscribing witnesses.

WIRT B. BOYCE.
